UNITED STATES PATENT OFFICE

WILLIAM R. STOCKWELL, OF MICHIGAN CITY, INDIANA, ASSIGNOR TO WEIL-MCLAIN COMPANY, OF MICHIGAN CITY, INDIANA, A CORPORATION OF DELAWARE

BOILER

Application filed March 17, 1928. Serial No. 262,532.

This invention relates to improvements in boilers.

One of the greatest difficulties encountered in striving for efficient fuel consumption in boilers, particularly boilers of the square sectional horizontal grate smokeless type, is that of maintaining uniformity of combustion over the entire grate area, i. e., maintenance of uniformity of the volume of air passing through the grate at all portions. In most boilers of the type indicated, the draft pull is at the rear end of the boiler, with a corresponding tendency to accelerate the air flow through, and hence the rate of combustion of, the fuel over those grate bars nearest the back of the boiler. This difficulty is further likely to be increased in so-called smokeless types of boilers which generally provide for an auxiliary supply of air near the rear of the boiler in order to promote secondary combustion.

In said square sectional types of boilers, wherein the vertical sections are arranged transversely, it is the common practice to so proportion the sections and the supporting base or frame that the end portions of the sections project beyond or overhang the side walls of the base or supporting frame, this arrangement permitting of smaller and consequently less expensive bases for a given size boiler section. Frequently it also happens that the number of sections placed one behind the other may vary in their total overall length from front to rear of the boiler so as to cause the rearmost section to partially overhang or project beyond the back wall of the base.

It is also well known to those skilled in the art that it is becoming increasingly important commercially and economically to provide insulation for boilers in order to minimize radiation losses and also to increase the aesthetic appeal of the boiler, the latter result being accomplished by providing metal sheathing which may be artistically finished in various colors with baked enamels and the like.

One object of my invention is to make use of the factors of overhanging sections and the desirability of sheathing the boiler, above

referred to, in providing an efficient smokeless type of boiler with uniform rate of air flow over the entire grate area, this being accomplished at a minimum amount of additional cost over that of the boilers as now commonly made. 55

Another object of my invention is to provide an improved arrangement for an auxiliary air supply for the grate in such manner that uniformity of air flow through the fuel bed and uniformity of combustion of the fuel is obtained. 60

A specific object of my invention is to provide an auxiliary air supply channel directly beneath the overhanging portions of the sections of a square section boiler whereby to minimize the space required for the boiler and at the same time avoid the necessity of any changes in the sections, themselves. 65

Other objects of the invention will more clearly appear from the description and claims hereinafter following. 70

In the drawings forming a part of this specification, Fig. 1 is a side elevation of a square sectional type boiler having my improvements incorporated therein, a portion near the base being broken away to illustrate certain features of the improvements. Fig. 2 is a rear end elevation of the boiler shown in Fig. 1. Fig. 3 is a vertical transverse sectional view corresponding to the line 3—3 of Fig. 1, but upon a somewhat larger scale. Fig. 4 is a horizontal sectional view corresponding to the section line 4—4 of Fig. 3. And Figs. 5, 6 and 7 are views corresponding respectively to Figs. 1, 2 and 4, but illustrating another embodiment of the invention. 75 80 85

Referring first to the construction illustrated in Figs. 1 to 4, inclusive, the boiler is shown of that type comprising a plurality of water sections A, one of which is shown in elevation in Fig. 3. Said sections, which are arranged transversely and placed one behind the other from front to rear of the boiler, are supported on a base which comprises side walls 10—10 and end walls 11 and 12, the base defining a rectangular ash pit below the horizontal grate, indicated at 13. The ash pit door is indicated at 14, the fuel feed door at 190

15 and one of the flue clean-out doors at 16. The sections A are provided with four flue openings 17, 18, 19 and 20, such that the products of combustion pass to the rear of the boiler in the fire pot or chamber 21, thence travel forwardly through the outside flues 17 and 20, the direction being reversed and the products then passing rearwardly through the central sets of flues 18 and 19 10 and finally into the hood 22 and thence from the latter through the flue pipe 23 to the chimney. In Figs. 1 and 2 I have indicated conventionally a bellows type governor 24 which actuates a lever 25, the latter having 15 a chain 26 running to a bar 27 which in turn is connected to and adapted to operate simultaneously two doors 28—28. The chain 26 is also connected to a lever 29 which in turn has a chain connection 30 to a check door 31.

20 Referring more particularly to Figs. 3 and 4, it will be noted that the lower ends 32 of the legs of the sections A are supported on the side walls 10 of the base and project outwardly beyond or overhang said walls 10, as clearly 25 shown in Fig. 3. I have shown the boiler sections covered with suitable heat-insulating material 33 which may be air cell asbestos and the layer of insulation in turn covered by a metal sheathing 34. The several sections will 30 be water-connected in the usual manner by nipples, the nipple openings being indicated at 35—36.

In the preferred embodiment of the invention, I employ secondary or auxiliary walls 37—37 which extend lengthwise of the boiler and are outwardly spaced from the corresponding side walls 10 of the base, as shown in Fig. 3. Each of said walls 37 may be in the form of a thin or light casting having 40 an inturned bottom flange 38 resting on the floor and provided also preferably with an inturned flange or shelf 39 near the top thereof, said flange 39 extending partially under the overhanging portions of the water sections. The main web of the wall 37 is 45 extended as indicated at 37', so as to partially overlap the lowermost portions of the section legs and thus leave a space within which is accommodated and held the lower edge 50 portions of the sheathing 34. In this manner, an efficient binder for the lower edge portions of the sheathing is obtained and a finished appearance given to the boiler.

From the preceding description, it will be 55 seen that I have provided two longitudinally extending air passages 40—40, one on each side of the boiler, each passage being defined by a side wall 10 of the base, the secondary wall member 37 and the overhanging portions 60 of the water sections, the latter being abutted one behind the other and thereby forming a closed top wall for the air passages. Said air passages 40 are closed at their front ends by the end portions of the 65 front wall 11 of the base, as shown in Fig. 4

and the same result is accomplished at the rear of the boiler by the extended ends of the rear wall 12. The latter, however, has the openings 41—41 through which the supply of air is admitted to the passages 40, said 70 openings 41 being controlled by the pivoted doors 28 which in turn are automatically controlled through the governor 24.

As indicated in a preceding part of the description, the tendency in boilers of the type disclosed where the draft pull is at the rear, is to produce accelerated combustion near the rear of the horizontal grate and in supplying the auxiliary air for smokeless combustion with my improvements, I counteract or balance the air draft by providing graduated series of communicating openings 42, 43, 44 and 45 in each of the base side walls 10, the largest opening being near the front of the boiler and the size of said openings gradually decreasing toward the rear, as clearly indicated in Figs. 1 and 4. In this manner, as the auxiliary supply of air is admitted through the door openings 41 of the rear of the boiler, the greater draft pull normally exerted near the rear and which would be effective through the smallest openings 45, is counterbalanced or neutralized by the fact that the larger openings 42 farthest from the admission door openings 41, permit the air 90 to pass through easier and in greater volume, although at a lesser rate. Thus air is supplied uniformly to the entire underside of the horizontal grate and a uniform rate of combustion obtained.

From the preceding description, taken in connection with the drawings, it will be observed that I utilize the space heretofore commonly wasted, i. e., the space normally left beneath the overhanging projections of the water sections. Further, a completely encased finished appearance is given to the boiler by the secondary wall members 37 which continue, in effect, the vertical sides of the boiler having the smooth appearance 105 provided by the sheathing 34. As understood by those skilled in the art, the sheathing 34 may be finished in any suitable manner to increase the aesthetic appearance of the finished boiler.

Referring to the modification illustrated in Figs. 5, 6 and 7, the arrangement of water sections, base, damper controls and the like is the same. In this modification, however, the modification has been adapted to those conditions where the rearmost water section B of the boiler projects beyond or overhangs the rear wall 112 of the base, which frequently happens. Under such conditions, I preferably provide a common air passage 140 along the rear end of the boiler, as best shown in Fig. 7, this being provided by an end auxiliary wall 237 which, with the auxiliary side walls 137—137, completes the two side air passages 140—140. Also, in this modifica- 125

tion, it is only necessary to employ one door 128 to govern the admission of air to the auxiliary air passages, it being understood that said door 128 is automatically controlled, as 5 in the case of the doors 28, previously described. Referring to Fig. 7, it will be observed that the air coming through the door opening 141 will divide, part going to the right and part to the left and thus supplying 10 both air passages 140, whence the auxiliary air is admitted to the ash pit space through the graduated series of openings 142, 143, 144 and 145.

In the modifications of Figs. 5, 6 and 7, 15 instead of providing separate castings to constitute the secondary walls 137 and 237, I preferably make the latter integral extensions of the boiler sheathing 134, i. e., the sheathing, both on the sides and rear end of the 20 boiler, is carried down to the floor line, as shown. This arrangement is somewhat cheaper than that disclosed in the first modification, and may be utilized when desired.

I have herein shown and described what I 25 now consider the preferred manner of carrying out my invention, but the same is merely illustrative and I contemplate all changes and modifications that come within the scope of the claims appended hereto.

30 I claim:

1. A boiler comprising: a base; a plurality of sections supported on said base, the bottoms of said sections projecting laterally beyond a wall of the base; means, separate 35 from the base and sections extending downwardly from said projecting portions and forming, with said corresponding wall of the base and the projecting portions of the sections, an air supply passageway closed along 40 the top by said projecting portions; and means providing communication between said passageway and the ash pit space within the base.

2. In a sectional boiler, the combination 45 with a base; of a plurality of sections mounted on said base and having the lowermost portions thereof projecting laterally beyond a wall of the base; an independent spaced wall member extending downwardly from the 50 overhanging portions of the sections and spaced from the corresponding wall of the base whereby to provide a closed air passage defined by the base wall, the spaced wall member and said overhanging portions of 55 the sections, the wall of the base having a graduated series of openings therein.

3. In a boiler of the character described, 60 the combination with a rectangular base; of a plurality of transverse water sections supported on said base and having the lower extremities of the sides thereof projecting laterally beyond the side walls of the base, said sections having flues so arranged as to 65 create the draft pull at the rear of the boiler; separate, secondary wall members extend-

ing lengthwise of the sides of the base and, with the latter and the overhanging projections of the sections, defining air passages closed along the tops by said overhanging projections, the side walls of the base having 70 openings therein decreasingly graduated from front to rear; and a door controlling the admission of air to said passages.

4. In a boiler, the combination with a base 75 having front, side and rear walls; of a plurality of transverse water sections supported on said base and having the lowermost portions of the sides thereof projecting laterally beyond the side walls of the base and the rear-most section projecting rearwardly beyond the rear wall of the base; secondary, separate wall members paralleling the side and rear end walls of the base and engaging the corresponding overhanging portions of said sections to thereby define side air passages and 80 a transverse rear air passage communicating with the side passages; means for admitting an auxiliary supply of air to said rear transverse air passage; and means for admitting air through the side walls of said base to the 85 interior thereof.

5. In a boiler, the combination with a plurality of assembled transverse water sections, the bottoms of which define a rectangle; of a 90 supporting base for said assembled sections, 95 said base being of rectangular form and of lesser width than the width of said rectangle formed by the bottoms of the sections, whereby the sections are supported by said base at points inwardly of each side of the assembled sections to thereby leave overhanging portions; secondary wall members, separate from the base, paralleling the sides of said base and disposed substantially vertically in line with the sides of the overhanging portions of the sections whereby to form therewith and the base, side air passages, the side walls of the base being apertured to provide 100 communication between said passages and the interior of the base; and means for admitting an auxiliary supply of air to said side air passages.

In witness that I claim the foregoing I have hereunto subscribed my name this 8th day of March 1928.

110 WILLIAM R. STOCKWELL.
